UNITED STATES PATENT OFFICE.

JOHN SPEICHER, OF JERSEY CITY, ASSIGNOR, BY DIRECT AND MESNE ASSIGNMENTS, TO THE NEWARK DISTRICT TELEGRAPH COMPANY, OF NEWARK, NEW JERSEY.

FIRE-ALARM BOX.

SPECIFICATION forming part of Letters Patent No. 408,762, dated August 13, 1889.

Application filed October 3, 1888. Serial No. 287,083. (No model.)

To all whom it may concern:

Be it known that I, JOHN SPEICHER, a citizen of the United States, residing at Jersey City, in the county of Hudson and State of New Jersey, have invented certain new and useful Improvements in Fire-Alarm Boxes; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The object of this invention is to provide a fire-alarm box more particularly for use in private houses, factories, and like positions, supplemental to the ordinary alarm system, of a reduced cost of construction and of greater simplicity, and one which will automatically transmit the number of the station, so that the location of the fire will be indicated at the central station.

The invention consists in the improved fire-alarm box or station having the arrangements and combinations of parts substantially as will be hereinafter set forth, and finally embodied in the clauses of the claim.

Referring to the accompanying drawings, in which like letters of reference indicate corresponding parts in each of the figures, Figure 1 is a front elevation of the improved box; and Fig. 2 is a section of the same, taken on line α .

In said drawings, a indicates a suitable box or case adapted to contain the circuit-breaking mechanism. b is a circuit-wheel pivoted in said box on an arbor c , which may be a screw. Said wheel is provided with a drum d , upon which a cord e is wound, and with a spring f , which gives return movement to the wheel after it has been turned the desired distance in one direction, the said spring being secured to a suitable fixture g and to the hub 45 of the wheel in any suitable manner. On the face of the wheel, near the periphery thereof, is an annular projection or rib h , which is open, as at i . Within said rib, concentric thereto, is formed a series of projections j ,

corresponding to or varying with the number 50 of the box.

Adjacent to the wheel b are arranged contact-springs k l , held by an insulated bracket m and connected with line-wires n n , one of said springs being provided with a lateral extension o , Fig. 2, which projects toward the face of the wheel and engages with the rib and projection h j . One end of the rib h , at the opening i , is provided with an inclined guiding-spring p , which extends toward and 60 close to the inner series of projections j .

By drawing on the cord e , connected with the circuit-wheel, the latter is made to turn from its normal position and to make an initial movement. At the beginning of this 65 movement the spring l , forming one of the terminals of the circuit, rides over the incline p onto the rib or projection formed on the wheel, as at h , the lateral extension o passing through the opening i , as will be understood. The extension o of the spring l remains on the rib h , held from engagement 70 with the signaling projections j during the whole of the said initial movement. At the end of the said initial movement or stroke 75 the spring is allowed to drop down through the opening i upon one of the series of projections j , the wheel having been brought back to or near its normal position. The operator then releases the cord e , and the wheel is 80 allowed to make a second or return movement, spring f acting to cause the wheel to move reciprocally in reverse direction. The spring l drops at each opening between the projections j , and thus breaks the contact between the 85 points k and l , and thus an alarm is transmitted to the alarm-bell. The movement of the wheel is impeded or governed by a governor q , which engages the toothed periphery b' of said wheel. Said governor retards the 90 movement of the wheel, so that the alarm mechanism on the main alarm-circuit has time to act. The spring p , held by the rib h at the close of the return or reverse movement of the wheel, allows the extension o of the 95 spring l to pass under it, so that when the wheel is again turned by the hand the extension will ride up the incline, as will be un-

derstood. The projections *j* of the wheel may be multiplied, so that by a single revolution two or more rounds of the alarm may be transmitted.

5. A galvanometer may be used in connection with the box to enable the line to be tested to locate interferences or breaks on the line.

Suitable stops for limiting the movement of the circuit-wheel are or may be provided, 10 as at *r* and *s*, one of said parts being on the wheel and the other on the box or other fixture.

Having thus described the invention, what I claim as new is—

15. In a fire-alarm box, a circuit-wheel, a rib *h*, open as at *i*, and a series of projections *j*, in combination with contact-points *k l*, one of which engages said rib and projections, substantially as and for the purposes set forth.

20. In combination, in a fire-alarm box, a circuit-wheel having teeth *b'*, a rib *h*, and projections *j*, corresponding with the number of the box, a spring *l*, having an extension *o*, a contact-spring *k*, and a governor, all said parts being arranged and operating substantially as and for the purposes set forth.

25. In combination, in a fire-alarm box, a circuit-wheel having a drum *d*, rib *h*, a concentric series of projections *j*, corresponding with the number of the signal-station, a spring *f*,

30. cord *e*, and governor, all said parts being arranged and combined substantially as and for the purposes set forth.

4. In a fire-alarm box, the combination of

the wheel *b*, having a spring *p*, rib *h*, and projections *j*, and a contact-spring *l*, having a lateral extension and co-operating contact-point, all said parts being arranged and combined substantially as and for the purposes set forth.

5. The combination, in a fire-alarm box, 40 with a reciprocating circuit-changer having a series of signaling projections thereon for changing the relations of the terminals of the circuit on which the box is stationed to one another, a rib or formation *h*, disposed on said changer adjacent to said signaling projections to hold one of said terminals during the initial stroke or movement of the reciprocating changer, and having a guide *p*, of a handle *e*, to allow the operator to give said initial movement, means, as described, for giving return movement to said changer, and said terminals arranged in said box adjacent to said changer and engaging the same, first during the initial stroke on the said rib or formation *h* and 55 then during the return-stroke on the signaling projections, all said parts being arranged and adapted to operate substantially as and for the purposes set forth.

In testimony that I claim the foregoing I have hereunto set my hand this 20th day of September, 1888.

JOHN SPEICHER.
